KEY CASE

Charles H. Dahlgren, West New York, N. J.

Application January 15, 1932, Serial No. 586,738

2 Claims. (Cl. 150—40)

This invention relates in general to key cases or key purses and more particularly to a key case the construction of which combines a number of novel and useful features.

5 An important object of the invention is the provision of a key case which has a single removable key holding member which may be pivotally swung outward and inward of the case and which may be readily detached therefrom to receive or discharge one or a number of keys.

Another important object of the invention is the provision in a key case of a key holding member, which, while capable of holding a plurality of keys, permits a selected key to be readily separated from the remainder, without removal from the holder, swung outward from the case as far away from the other keys as possible and readily manipulated for the opening operation without interference with the other keys.

20 Still another important object of the invention is the provision in a key case of a backing plate, made of a single piece of sheet metal and adapted to perform four important functions: 1. To serve as a novel bearing for the key holding member, 25 2. To hold a removable sheet or card bearing the name and address of the owner of the key case, 3. To act as a stiffening or reinforcing member for the whole case and 4. To provide an anchorage for a key case chain.

30 Yet another important object of the invention is the provision of a key case, having the foregoing combined advantages, which has few and simple parts, which may be manufactured with economy and speed, and which when finished will 35 take up little space and present an attractive appearance.

Numerous other objects of the invention will be apparent as it is better understood from the following description, which, taken in connection 40 with the accompanying drawing, discloses a preferred embodiment thereof.

In the accompanying drawing:

Figure 1 is a perspective view showing the case in open position with a selected key ready for its 45 opening operation.

Fig. 2 is a side elevation of the closed key case.

Fig. 3 is a similar view showing the back of the closed case.

Fig. 4 is an elevational view, partly in section, 50 showing a side flap of the flexible cover and the keys in resting position within the case.

Fig. 5 is a fragmentary detail view showing the bearing part of the backing plate and the pivotal part of the key holding member in outwardly extended position, as in Fig. 1.

Fig. 6 is a sectional detail view taken along the lines 6—6 of Fig. 5, and illustrating how the backing plate is secured to the flexible cover by riveting.

In the preferred embodiment of the invention shown in the drawing, reference numeral 1 indicates a cover or casing of leather or other suitable flexible material. This cover comprises a back portion 2 and side wings or flap portions 3 and 4. The flap 3 of the cover is adapted to fold over the keys when the key case is in closed position (as in Fig. 2) and the flap 4 being slightly larger than flap 3 is adapted to overlie flap 3 and to be removably secured to the back 2 by means of a snap button 5, secured adjacent the tip or tongue 6 of the flap 4, taking over a snap boss 7, projecting from the back 2 at about its longitudinal center.

Substantially co-extensive with the back 2 and secured to its inner surface by means of rivets 8 20 and 9, is a backing plate 11 made from a single, substantially rectangular, piece of sheet metal or other suitable material slightly widened at one end. The longitudinal marginal edges of the plate 11, up to the widened part, are turned upwardly and inwardly in reverse directions to form guide grooves or flanges 12. A name plate 13 of celluloid or other suitable material and bearing the name and address of the owner of the keys, may be slid between the guide flanges 12 of the 30 plate. One end of the plate 11 may be slightly tapered to conform to the tapered cut of the cover and may be used as an anchorage. A chain 14 may be suitably secured to the rivet 9 at the tapered end of the plate. The opposite widened 35 end of the plate 11 serves as a bearing or anchoring means for the key holding member. This end has the material of its side edges bent upwardly and outwardly to provide bearing flanges 15 and 16, having circular bearing holes 17 and 18 of a 40 diameter equal or slightly larger than the diameter of a key holding member 19.

This key holding member or wire loop 19, preferably, is substantially U-shaped in outline, bent from a single piece of resilient wire and has a 45 rounded closed U-bottom 21 and U-legs 22 and 23. The legs 22 and 23 are bent inwardly at right angles to provide bearing pins 24 and 25 adapted to take through the bearing holes 17 and 18. U-leg 23 is a little longer than leg 22 50 and its free end is bent at a right angle to the pin portion 25 to provide a stop 26 for the latter and prevent its accidental detachment from the bearing hole 18.

When keys are placed upon the key holder, a 55

preferable manner of accomplishing this operation is as follows:

The key holder is grasped by the rounded bottom 21 and is held at a right angle to the plate 11, with the stop 26 inserted through the bearing hole 18. The holder is then swung around into parallelism with the plate 11, with the pin 24 still free of engagement with the bearing hole 17. As many keys as are desired to be placed upon the holder and can be carried by it are now inserted by their perforated heads upon the pin 24 and slid along the leg 22 until the bunch of keys come to ride upon the rounded part 21 of the holder. The leg 22 is then sprung outwardly and the pin 24 snapped into the bearing hole 17. The bunch of keys with their perforated heads riding upon the rounded part 21, are then grasped and swung towards the tapered end of the plate 11, together with the holder 19, which come to rest against the plate 11. The keys are given another pivotal movement, a kind of jackknife movement relative to the now resting holder until the keys come to lie between the legs 22 and 23 with their heads resting upon the tapered end of the plate (as in Fig. 4) and their shanks extending toward the bearing end of the plate. The flanges 15 and 16 of the plate 11 may be shaped or bent in such manner as to function as reversely directed cam surfaces and key holder locks or stops. Their construction, as shown in Fig. 5, will cause the inner surfaces of the legs 22 and 23 adjacent the pins 24 and 25 to ride upon the outer edges of the flanges, forcing the legs apart, when the key holder is moved from resting position shown in Fig. 4 to extended position shown in Fig. 1. The natural resiliency or spring-like quality of the legs will then cause them to snap back under said flanges when they have cleared the wide outer edges of the flanges and the latter will hold the legs in yielding locking position as clearly shown in Fig. 5.

The flaps 3 and 4 at the tapered end of the plate 11 may be stitched or otherwise secured together in a seam 27 (Fig. 2) to present a nicely finished appearance.

It will thus be seen that the finished key case 5 consists of a well planned combination of simple parts, compactly and economically put together with a view to place upon the market a useful, inexpensive and neat appearing article.

It is thought that the invention and many 10 of its attendant advantages will be understood from the foregoing description and it will be apparent that various changes may be made in the form, construction and arrangement of the parts without departing from the spirit and scope of 15 the invention or sacrificing all of its material advantages, the form herein before described being merely a preferred embodiment thereof.

I claim:

1. In a key case, in combination, a flexible 20 cover, a plate secured along the longitudinal center of said cover, a key holder pivotally secured to said plate and adapted to hold a plurality of keys and permit movement of a selected key a substantial distance away from the remaining keys, opposed edges of said plate being flanged in reverse directions to form a pivot for said holder and to support a name card.

2. In a key case, in combination, a flexible 25 cover, a metal backing and key holder anchoring plate connected with said cover, a U-shaped key holder having its free ends pivotally connected with said plate adjacent one end of said plate, the metal of said plate adjacent said end being turned in opposite directions to provide cam 35 flanges adapted to spread said holder when the latter is moved in one direction and adapted to lock said holder when moved in the opposite direction.

CHARLES H. DAHLGREN. 40
